CLOSURE FOR NONREFILLABLE BOTTLES

Filed Aug. 15, 1927

Inventor:
A. Hafermann

By: Marks & Clark
Attn:

UNITED STATES PATENT OFFICE

ALFRED HAERMAN, OF BERLIN-LICHTENRADE, GERMANY

CLOSURE FOR NONREFILLABLE BOTTLES

Application filed August 15, 1927, Serial No. 213,128, and in Germany September 6, 1926.

This invention relates to closures for non-refillable bottles and has for its object to provide a closure of this kind having no complicated valves and no cap embracing the 5 bottle neck.

The closure is particularly simple in construction and consequently very cheap to manufacture.

In the accompanying drawing several 10 constructional examples of the closure according to the invention are shown diagrammatically, Figures 1 and 2 being vertical sections through two constructional forms, having no movable parts, and Figure 3 a corresponding 15 cross-section, Figures 4 and 5 vertical sections through two constructional forms with quite simple valves, for which Figure 3 can also be taken as representing a cross-section, without showing the valves, however.

20 Referring to Figures 1 to 3, in the bottle neck 1 a cork ring 2 or some other packing is provided. Inside the said cork ring is an annular dished member 3, suitably made of porcelain, the inner rim of which in the form 25 shown in Fig. 1 is lower than the outer rim, while in Fig. 2 a second cork ring 4 or the like is provided for keeping the second insertion to be referred to below at a suitable distance from the inner rim of the dished member 3. The second insertion 5 just referred 30 to, which rests on the outer rim of the dished member 3 or on the said second ring, is provided with an inner cylindrical extension 6 which forms an inverted dished member 35 below the extension and projects into the annular space in the dished member 3, without being in contact with the walls of the same. From two oppositely located points of the insertion 5, inclined passages 7 and 8 extend 40 upwards in such a manner that they commence outside the cylindrical extension 6 and open in a vertical bore or recess 9, provided in the upper part of the insertion 5. In Figure 1 this opening 9 is eccentric and the passage 7 enters it from below. A cork ring 10 is inserted in the recess 9 for holding the spout or outlet proper 11. The other passage 8 opens above the cork ring 10 and communicates there with the outer air. According 45 to Fig. 2 the two passages 7 and 8 open

into the bottom of the recess 9 and in the spout 11 opposite the outlet opening is an air vent 12.

After the bottle has been filled the parts 2 to 9 referred to are inserted, the spout being 55 in the meantime replaced by a cork stopper. The spout is only inserted when the bottle is to be used. If the bottle be then tilted when pouring out, the liquid passes out through the 60 lower lying part of the dished member 3, the passage 7 and the spout 11, while air enters through the air vent 12, the passage 8 and the higher lying part of the dished member 3. If, after the removal of the spout 11 and 65 stopping up one of the two passages 7 or 8, an attempt be made to pour in liquid, this will be found impossible, as the liquid in the dished member 3 prevents the escape of air and the entrance of liquid.

If desired, additional safety means covering the inner opening in the inserted part 3 may be provided, as shown in Figures 4 and 5. In the arrangement shown in Fig. 4 a valve pin 14 provided with a top plate or cone 13 is inserted in the said opening, the 70 lower end of which is suitably thickened for increasing its weight to a certain extent. In the constructional form shown in Fig. 5 the cylindrical extension 6 is omitted from the insertion 5 and in its place an inverted dished member 15 is provided, which when in the 75 position of rest, covers the said opening.

The bottle closure and the bottle to be used with it may be made of any suitable material, for instance, of metal. The cork rings 2 and 4 could then be replaced by screwing, riveting, bolting or the like. Similarly with glass or porcelain bottles, the cork rings 2 may be replaced by fluted, roughened and cemented 80 parts, as indicated in Figure 2.

90 What I claim is:

1. A closure for non-refillable bottles comprising in combination an annular dished member inserted in the neck of the bottle, said member having an upwardly extending inner rim, an outer closing member inserted in the neck of the bottle above said annular dished member, an inverted dished member below the said closing member and extending downwardly into the said annular dished 95 member, two inclined passages communicating with the outer air, and an air vent 100

- member over the inner rim thereof without touching the walls of the dished member, passages in said outer closing member, extending upwardly therein from the part of the bottom thereof outside the said inverted 5 dished member, for allowing the escape of liquid from the bottle and the admission of air thereto when pouring out the contents of the bottle, the inverted dished member below said closing member being adapted to coact 10 with said upwardly extending inner rim so as to trap a quantity of liquid in the annular dished member, sufficient to prevent liquid being poured into the bottle, through said passages, as set forth.
- 15 2. A closure for non-refillable bottles as claimed in claim 1, and comprising a valve capable of resting on the inner rim of the annular dished member and closing the middle opening of the said annular dished member when the bottle is upright and of being raised from said inner rim so as to uncover the said middle opening, when the bottle is tilted for pouring out the contents, as set forth.
- 20 25 In testimony whereof I have signed my name to this specification.

ALFRED HAFFERMANN.
